UNITED STATES PATENT OFFICE.

JOHN A. COHEE, OF NARBERTH, PENNSYLVANIA.

DESIGN FOR A CHILD'S CHAIR.

Application filed June 22, 1921. Serial No. 479,659. Term of patent 7 years.

To all whom it may concern:

Be it known that I, JOHN A. COHEE, a citizen of the United States, residing in Narberth, county of Montgomery, and State of Pennsylvania, have invented a new, original, and ornamental Design for a Child's Chair, of which the following is a specification, reference being had to the accompanying drawing, which forms a part thereof.

The figure is a perspective view of a child's chair embodying my design.

I claim—

The ornamental design for a child's chair, as shown.

In testimony of which invention, I have hereunto set my hand, at Philadelphia, on this 20th day of June, A. D. 1921.

JOHN A. COHEE.
